UNITED STATES PATENT OFFICE

2,025,364

GAS GENERATING PROCESS

Jay E. Tone, Des Moines, Iowa

Application November 12, 1930, Serial No. 495,095

1 Claim. (Cl. 23—150)

An object of my invention is to provide an economical and efficient process for producing an inert gas particularly CO_2 by means of an apparatus such as the one disclosed in my copending 5 patent application, Serial No. 370,759, filed June 14, 1929 (Patent 1,984,665, Dec. 18, 1934) and of which application the present one is a continuation in part.

More particularly, it is my object to provide 10 a process in which charcoal or other fuel appropriate for producing the desired gas is initially burned and the gas and smoke removed therefrom and disposed with, after which the partially burned charcoal, which is then in the form of 15 glowing coals, is secondarily burned and air is forced through the charcoal while being secondarily burned whereby to produce an inert gas.

With these and other objects in view my 20 invention consists in a process whereby the objects contemplated are attained, as hereinafter more fully set forth, pointed out in my claim and illustrated in the accompanying drawings in which:—

Figure 1 is a side elevation of a portion of an 25 apparatus used in performing the process.

Figure 2 is a vertical sectional view through the same on the line 2—2 of Figure 1.

Figure 3 is a horizontal sectional view taken 30 on the line 3—3 of Figure 1 illustrating the gas take-off portion of the apparatus.

Figure 4 is an end elevation of a portion of the 35 operating mechanism of the apparatus.

Figure 5 is a sectional view on the line 5—5 of Figure 1, illustrating the reverse side of the 40 mechanism shown in Figure 4 and

Figure 6 is a diagrammatic view of an apparatus for producing the gas of the process.

In the packing of coffee in metal cans, the 45 vacuum pack system has been extensively used. The vacuum pack system consists in filling the can with ground coffee and then removing the air therefrom by vacuum. It is well known that a perfect vacuum cannot be attained and therefore, a small quantity of air remains in the coffee can. This air has a deteriorating effect on the 50 quality and taste of the coffee, the amount of deterioration increasing with age.

I have attempted to eliminate such a 55 contingency by substituting for the air removed from the can, an inert gas and a small amount of reducing gas such as carbonmonoxide. I have found that the introduction of an inert gas into the coffee will neither harm it nor deteriorate the flavor and quality of the coffee even though left in the can indefinitely.

One way of producing an inert gas is to burn charcoal and draw air through the burning charcoal whereby an inert gas results. However, a gas produced in this manner also draws the smoke 60 from the charcoal and other gases of combustion

and even though the smoke is very small in quantity, it has a tendency to affect the flavor of the coffee.

I have, therefore, endeavored to provide a process wherein the smoke and gases are first removed from the charcoal as it is being burned and thereafter the burning charcoal is introduced into a combustion chamber through which air is drawn and this air I find becomes an inert gas lacking the odorous and foreign taste imparting 10 elements common to gas produced from charcoal which is only burned once and the air passed directly through it while burning. I will now describe an apparatus which may be used for producing an inert gas by my improved process. 15

The apparatus is shown on the drawings, 10 indicating a secondary combustion chamber which is substantially cylindrical in cross section. Legs 12 are secured to the chamber 10 for supporting the same relative to a floor 14. 20

Supporting members 16 are secured to the top of the combustion chamber 10 and support on their upper ends, a combustion chamber 18. I will refer to the combustion chamber 10 as a secondary combustion chamber and to the combustion chamber 18 as a primary combustion chamber. 25

A charcoal container 20 is supported on the upper end of the primary combustion chamber 18 and has positioned therein, a feed hopper 22. 30 A removable lid 24 is provided for the hopper 22. The hopper 22 may be filled with charcoal as indicated at 26 which settles by gravity through a thimble 28 and spreads as indicated at 30 over the bottom of the primary combustion chamber 35 18.

The combustion chamber 18 is in the shape of an inverted cone and its bottom is formed by a plurality of rotatable grates 32, 34 and 36. The grates 32, 34 and 36 have their ends journaled in bearing members 38 and 40. The members 38 and 40 are secured as indicated at 42 to the supporting members 16. The shaft 44 of the grate 32 extends beyond the bearing member 38 and through a bracket 46. Between the bracket 45 46 and the bearing member 38, a ratchet wheel 48 is provided.

An actuating arm 50 is secured to a sleeve 52 which surrounds the shaft 44 and extends through a bearing 54 formed on the bracket 46. Secured 50 to the sleeve 52 between the bracket 46 and the ratchet wheel 48, is a hub 56 from which extends a pawl arm 58. A pawl 60 is mounted on the free end of the arm 58 and is adapted to engage the teeth of the ratchet wheel 48. 55

A gauge plate 62 is rotatably mounted on the shaft 44 adjacent the ratchet wheel 48. A pawl engaging flange 64 is formed on the gauge plate 62, the purpose of which will hereinafter be referred to. The gauge plate 62 may be adjusted 60

by rotation and for holding it at any of its adjusted positions, threaded studs 66 are provided thereon extending through slots 68 in the bracket 46. Clamp wing nuts 70 are provided on the 5 studs 66.

A substantially cone-shaped deflector 72 is mounted between the primary combustion chamber 18 and the secondary combustion chamber 10. The deflector 72 is supported in position relative 10 to the supporting members 16 by means of rivets or the like 74.

The top of the combustion chamber 10 is formed by a plate 76 secured thereto and on which an annular manifold 78 is formed. Within 15 the manifold 78, an annular passageway 80 is provided which communicates by means of openings 82 with the interior of the combustion chamber 10. The top of the manifold 78 is substantially cone-shaped and its top surface is in alignment with a cone-shaped surface 84 formed on a removable thimble 86. The combustion chamber 10 is formed with an extension 88 terminating in a head 90. An inspection glass 92 is mounted in the head 90 for the purpose of viewing 20 the interior of the combustion chamber 10.

The bottom of the combustion chamber 10 is formed by a rotatable grate supporting member 94 and a head 96. Removable grate members 98 are supported by the member 94 and the head 30 96. The grate members 98 are substantially triangular-shaped and the head 96 being higher than the grate supporting edge of the member 94, the grate members form a substantially cone-shaped rotatable grate.

35 The periphery of the member 94 is corrugated as indicated at 100 and the lower inner periphery of the combustion chamber 10 is corrugated as indicated at 102. The grate supporting member 94 and the head 96 are secured to a shaft 104. The shaft 104 is rotatably mounted in a casing 106 provided with supporting arms 108. The arms 108 as indicated at 110 are secured to the supporting 40 legs 12 of the device.

An adjustable thrust screw 112 is mounted in 45 the bottom of the casing 106 for the purpose of supporting the shaft 104 and the parts secured thereto. Within the casing 106 a bevel gear 114 is secured to the shaft 104. A bevel pinion 116 (best shown in Figure 1 of the drawings) is 50 mounted on a shaft 118 journaled in one side of the casing 106 and in mesh with the bevel gear 114. The shaft 118 extends through a bracket 46a supported on extensions 120 which are in turn secured to the supporting legs 12 of the device.

55 The parts supported with relation to the bracket 46a and the shaft 118 are identical to the parts bearing the reference numerals 48 to 70 as already described in connection with the grates 32, 34 60 and 36. I will therefore refer to similar parts for operating the shaft 118 with similar reference numerals with the addition of the distinguishing character *a*.

A boss 122 is formed on the manifold 78 into 65 which a pipe line 124 is screwed. The pipe line 124 extends to an intake pipe 126 formed on a separator 128. It will be noted by referring to Figure 3, that the intake pipe 126 of the separator 128 is arranged tangentially relative to the 70 separator.

The separator 128 is substantially cylindrical in cross section and has a downwardly extending cone-shaped portion 130 terminating in a reduced cylindrical portion 132. A removable cover plate 75 134 held in position by bolts 136 and wing nuts

138, is mounted on the lower end of the cylindrical portion 132. Leg members 140 and braces 142 are provided for supporting the separator 128 relative to the floor 14. Within the separator 128 an annular baffle wall 144 is provided extending 5 downwardly from the top of the separator and spaced from the outer wall thereof. Connected with the top of the separator 128 and communicating with the portion of the separator inside of the baffle wall 144, is an outlet pipe 146. 10

Referring to the diagrammatic view shown in Figure 6, the outlet pipe 146 communicates with a shut-off control valve 148. The control valve 148 is connected with a condenser 150 which is merely a plurality of tubes cooled by atmosphere and may, in practical construction, be a steam or hot water radiator. 15

A pipe line 152 leads from the condenser 150 to the air chamber 154 of a compressor 156. The valve box of the compressor 156 is indicated at 158 and from the valve box, a pipe line 160 extends. The pipe line 160 may discharge into a storage tank wherein the gas may be stored for immediate or future use as desired. Suitable automatic controlling devices may be utilized for 25 regulating the pressure of the gas introduced into the storage tank.

Practical operation

In the practical operation of the apparatus 30 herein disclosed, the lid 24 is removed and the hopper 22 filled with charcoal as indicated in dotted lines at 26 in Figure 2 of the drawings. The charcoal feeds downwardly by gravity assuming approximately the position with respect to the 35 primary combustion chamber 18 indicated at 30 and resting on the grates 32, 34 and 36. The charcoal resting on the grates is ignited by means of a blow torch or a gas torch which might be operated by the city gas and permanently attached to the machine.

After being ignited, the charcoal burns on the 40 grates 32, 34 and 36 and whatever little smoke there is arising from the burning charcoal and some of the gas therefrom, pass upwardly in the 45 container 20 and are discharged to atmosphere through a chimney 162. The burning of the charcoal on the grates may be controlled by means of a damper 164 mounted in the chimney 162. Preferably the chimney 162 extends to the 50 intake side of an exhaust fan or blower 212, and from the top side thereof to a chimney or smoke stack. The blower 212 is operated by an electric motor 214 or may be driven from the compressor 127 if desired. A sliding check door may be provided in the chimney 162 so that cool air can be admitted to the gas being drawn by the blower from the casing 20 if desired. 55

My generating machine may or may not include a shield 216 (see Figure 2) extending from the 60 chamber 18 to the flange 76 of the manifold 80. The shield 216 may be provided for the purpose of preventing the escape of gas into the atmosphere of the room in which the apparatus is located, such gas arising from the charcoal burning above the thimble 86. The shield when used is open on one side as shown in Figure 3. Thus, whether the shield is used or not, air is supplied 65 freely above the thimble and below the grates of the primary combustion chamber. The interior 70 of the shield 216 is preferably connected by means of a pipe 220 with the chimney 162. A damper 218 and slide check door 222 are provided for controlling the draft of air through the pipe 220. It will be noted that the pipe 220 being 75

connected with the chimney 162 (see the diagrammatic view, Figure 6) whereby the blower 212 serves for drawing gas from both the interior of the hopper casing 20 and the shield 216.

5 The grate 32 is slowly rotated by oscillating the arm 50. For oscillating the arm 50, I provide an actuating device A including a casing 166 having a shaft 168 journaled therein.

A crank arm 170 is secured to the shaft 168 and 10 through the medium of a link 172, oscillates the arm 50. Oscillation of the arm 50 causes the arm 58 to oscillate and thereby rotate the ratchet wheel 48 intermittently through the medium of the pawl 60. During each oscillation of the arm 15 58, the pawl 60 may rotate the ratchet wheel 48 any desired number of teeth therein by adjusting the gauge plate 62.

Referring to Figure 5 for instance, adjustment 20 of the plate 62 in the direction of the arrow 174 will cause the pawl 60 to disengage the teeth of the ratchet wheel 48 due to the undersurface thereof engaging the flange 60 sooner upon oscillation of the arm 50 in the direction of the arrow 176 and therefore, the next tooth engaged by the 25 pawl 60 will not be moved as far in the direction opposite to the arrow 176 as when the plate 62 is adjusted in the direction opposite to the arrow 174.

For rotating the shaft 168 and thereby rotating 30 the grate 32, a pulley 178 is provided which may be belted by means of a belt 125 and pulley 127 to the shaft of the compressor 156 or run by an independent motor.

A pin 180 is provided on the shaft 44 of the 35 grate 32 and pinions 182 are provided on the grates 34 which mesh with the pinion 180. A pinion 184 on the shaft of the grate 36, meshes with one of the pinions 182.

From the construction of the parts just 40 described, it will be obvious that rotation from the grate 32 is imparted to the grates 34 and 36. Disc like end portions 186 are provided on the grates 32, 34 and 36 for forming substantial end members slightly spaced from the irregular shaped 45 lower edges 188 of the primary combustion chamber 18.

As the grates 32, 34 and 36 are slowly rotated, the partially burned charcoal now in the form of glowing coals falls into the deflector 72 and 50 then through the thimble 86 and into the combustion chamber 10 where it piles up on the grate members 98 as indicated in dotted lines at 190 in Figure 2. The partially burned charcoal also fills the thimble 86 and assumes the position 55 indicated at 192 whereby the thimble 86 and the space between the corrugated surfaces 100 and 102, is substantially filled. As the partially burned charcoal is burned in the secondary combustion chamber 10, the grate members 98 are slowly rotated through the medium of the bevel gear 114, the bevel pinion 116, the shaft 118, the ratchet wheel 48a, the pawl 60a, the pawl arm 58a, the sleeve 52a and the arm 50a.

The arm 50a is operatively connected by a link 60 194 to a crank arm 196 mounted on a shaft 198. The shaft 198 is journaled in the housing 166 of the gearing mechanism A and is operatively connected with the rotating shaft 168 by means of a worm gear 200 and a worm 202. The mechanism 70 A is mounted on a bracket 204 which may be secured to the wall or to the container 20 if found desirable.

As a vacuum is produced in the condenser 150, atmospheric pressure will force air up through

the spaces between the corrugated portions 100 and 102 in the bottom of the secondary combustion chamber 10 and down through the thimble 86 thereof. Such air in passing through the burning charcoal forms an inert gas free from oxygen 5 and smoke produced when burning the charcoal in the primary combustion chamber.

This inert gas is forced by the atmospheric pressure through the openings 82 in the cover plate 76 of the combustion chamber 10 and into 10 the manifold 78. It will be noted by referring to Figure 3, that the openings 82 vary in size whereby the pressure is equalized throughout the manifold 78 and there is a substantially even distribution of inert gas passing through the openings 82 into the annular passageway 80.

From the passageway 80, the inert gas is discharged tangentially into the separator 128 whereby it is given a whirling motion before passing beneath the annular baffle wall 144 and into 20 the discharge pipe 146 from whence the gas travels through the condenser and cooler 150 to the compressor 156. The separator 128 receiving the gas in a whirling motion, causes any particles of charcoal ash which might have been collected 25 thereby, to settle toward the outer surface of the separator due to centrifugal force. Then by gravity such particles drop into the cylindrical portion 132 from which they may be removed at intervals by removing the cover plate 134. 30

The condenser 150 is provided so that the gas will not leave the compressor 156 in a hot and expanded condition which would throw unnecessary work onto the compressor for having to compress an expanded gas. Therefore, by providing a condenser and cooler 150, a compressor 156 of small capacity can be used for extracting the inert gas from the gas producing apparatus. 35

When cleaning out the combustion chambers 10 and 18, the grates 32, 34 and 36 and the grate 40 members 98 may be manually rotated by a crank 206. The crank 206 is provided with slots 208 adapted to engage pins 210 extending through the shafts 44 and 118.

By operatively connecting the gear box A with 45 the compressor 156, the speed of rotation of the grates of the combustion chambers and consequently the burning rate of the charcoal can be regulated with respect to the capacity of the compressor. Automatic control means for the damper 164 might also be provided whereby the burning rate of the charcoal could be controlled depending on the consumption of the inert gas or other factors. 50

Changes may be made in the specific manner 55 of performing my process without departing from the real spirit and purpose of my invention and it is therefore my intention to cover by my claim, such modified methods of performing the process as may be reasonably included within their scope. 60

I claim as my invention:

The process of producing an inert, non-oxidizing gas which comprises initially igniting and partially burning a mass of charcoal in a primary combustion chamber until smoke and gases 65 are removed therefrom, transferring the burning charcoal to a secondary combustion chamber and while still hot forcing air through the glowing charcoal thereby forming an inert gas free from oxygen and smoke, drawing off such inert gas, 70 separating the solid impurities from the gas and cooling and collecting said gas.

JAY E. TONE.
